UNITED STATES PATENT OFFICE.

EDWIN O. PRESBY, OF NEW YORK, N. Y.

DRAWERS-SUPPORT.

SPECIFICATION forming part of Letters Patent No. 533,373, dated January 29, 1895.

Application filed October 25, 1894. Serial No. 526,964. (No model.)

To all whom it may concern:

Be it known that I, EDWIN O. PRESBY, a citizen of the United States, residing at New York, in the county of New York and State of New York, have invented certain new and useful Improvements in Drawers-Supports; and I do hereby declare the following to be a full, clear, and exact description of the invention, such as will enable others skilled in the art to which it appertains to make and use the same.

My invention relates to improvements in drawers supports to be attached to trousers, and it consists of certain novel features hereinafter described and claimed.

Reference is had to the accompanying drawings, wherein the same parts are indicated by the same letters throughout the several views.

Figure 1 represents a perspective view showing the improved drawers supporter attached to the waistband of a pair of trousers, and supporting the drawers. Fig. 2 represents a section, on an enlarged scale, of the device shown in Fig. 1, along the line *x* of the said figure; and Fig. 3 represents another form of device for attaching the drawers supporter to the waistband of the trousers, being shown in section similar to that of Fig. 2.

A represents the trousers provided with a waistband of the usual type.

B represents the drawers provided with ordinary tapes *b*, by which the said drawers are ordinarily attached to the suspender buttons of the trousers.

C represents a suspender button of the usual type secured to the waistband of the trousers, by the flanges *c*. Attached to the said flanges is a resilient head *c'* which snaps into the recess *d* in the center of the metal cap *D*, which is preferably made of two pressed plates *d* and *d'* engaging each other as shown most clearly in Fig. 2. Attached to this metal cap *D* is a supporting strap *E* made of tape, braid, elastic, or other suitable material, which is bent on itself as at *e*, and carries a second cap *D* by means of which the free end may be secured to a similar resilient head *c'* attached to the shank *C'* as shown in Fig. 2, or to a resilient head *d'* attached to the cap *D'*, as shown in Fig. 3.

The construction shown in Fig. 3 is preferred, since the shank of the button *C* serves to support both ends of the supporting strap *E* and the necessity for a second button or shank *C'* is obviated.

55

The herein described supporter is readily detachable, and may be transferred from one pair of trousers to another, or removed altogether, as desired.

Instead of connecting the supporting strap 60 *E* to the button *C*, the upper end thereof may be sewed or riveted to the trousers, and the free end may be secured in the supporting position, as by the shank *C'*, and the cap *D'* shown in Fig. 2; or the two caps *D'* and *D*, 65 shown in Fig. 3, may be used, the upper end of the strap *E* being sewed or riveted to the waistband of the trousers, and not being connected to the button *C*.

Having thus described my invention, what 70 I claim, and desire to secure by Letters Patent of the United States, is—

1. A combined clasp and button, consisting of a button provided with a rigid shank, a resilient head attached to said shank, a metal 75 cap adapted to snap over said resilient head and carrying on the back thereof a second resilient head, and a second metallic cap adapted to snap over said second resilient head, substantially as and for the purposes 80 described.

2. A combined clasp and button consisting of a button provided with a rigid shank, a resilient head attached to said shank, a metal cap adapted to snap over said resilient head 85 and carrying on the back thereof a second resilient head, a second metallic cap adapted to snap over said second resilient head, and a strip of flexible material secured to each of said metallic caps, substantially as and for 90 the purposes described.

In testimony whereof I affix my signature in presence of two witnesses.

EDWIN O. PRESBY.
